UNITED STATES PATENT OFFICE.

FRANK LANSBERG, OF ST. LOUIS, MISSOURI, ASSIGNOR TO THE LANSBERG BRAKE COMPANY, OF EAST ST. LOUIS, ILLINOIS.

AIR-BRAKE.

SPECIFICATION forming part of Letters Patent No. 415,515, dated November 19, 1889.

Application filed March 1, 1889. Serial No. 301,624. (No model.)

To all whom it may concern:

Be it known that I, FRANK LANSBERG, of the city of St. Louis, in the State of Missouri, have invented a certain new and useful Improvement in Air-Brakes, of which the following is a full, clear, and exact description, reference being had to the accompanying drawings, forming part of this specification, and in which—

10 Figure I is a longitudinal section illustrative of my improvement and taken on line I I, Fig. III. Fig. II is a section taken on line II II, Fig. III. Fig. III is a transverse section taken on line III III, Fig. II. Fig. IV is a transverse section taken on line IV IV, Fig. II. Fig. V is a section taken on line V V, Fig. IV.

15 My invention relates to certain improvements in air-brakes for railway-cars and my invention consists in features of novelty hereinafter fully described, and pointed out in the claims.

20 Referring to the drawings, 1 represents part of the train-pipe; 2, part of the pipe leading to the receiver, and 3 part of the pipe leading to the brake-cylinder.

25 4 represents a port leading from the train-pipe to a chamber 5. Located in the port 4 is an enlargement 6, cut off from the port 4, 30 save for a small passage-way 7, by means of lips or flanges 8. The object of this enlargement is to receive and collect the dust and foreign matter in the air and keep them from entering the valve-chamber. In the chamber 35 5 is a piston 9, secured to one end of a stem 10. On the other end of the stem 10 is a piston 11, smaller than the piston 9. This piston 11 is located in a chamber 12, communicating with the chamber 5. On one side of the stem 40 10 is a rack 13. On the other side of the stem there is an arm 14, the outer end of which fits between longitudinal ribs or guides 15, to keep the stem of the pistons from turning. The 45 rack 13 is engaged by a segment 16. This segment (see Fig. IV) is secured to the end of a three-way cock or valve 17.

50 18 represents a port leading from the chamber 12 to the chamber 5, thus forming a communication between the two chambers around the pistons 9 and 11. In the port 18 is located

a valve 19, as shown in Figs. II and III. The pipe 2 of the receiver communicates with the port 18, through means of a port 20. (See Fig. IV.) In the port 20 the valve 17 is located. The port extends beyond the valve and communicates with the brake-cylinder pipe 3. (See Figs. IV and V.)

The operation is as follows: The air passing through the train-pipe enters the chamber 5 through the port 4. On entering it moves the pistons 9 and 11 from the position shown in Fig. I to the position shown in Fig. II. This opens communication between the ports 4 and 18, (the port 18 being provided with a check-valve 19 for the purpose of regulating the pressure in the receiver,) and the air passing through the ports 4 and 18 (the valve 19 opening under the pressure) passes out through the pipe 2 to the receiver. As soon as the pressure in the train-pipe is released, the check-valve 19 closes, and the pressure behind the piston 11 moves the pistons 9 and 11 from the position shown in Fig. II to the position shown in Fig. I. This shuts off communication between the ports 4 and 18 through the chamber 5, and at the same time opens communication between the receiver and the brake-cylinders by operating the valve 17 through means of its described connection with the stem 10 of the pistons 9 and 11, the valve making one-quarter of a turn from the position shown in Fig. V. As soon as the pressure in the train-pipe again exceeds that of the receiver, the pistons 9 and 11 are moved again from the position shown in Fig. I to the position shown in Fig. II, and the air passes to the receiver, as described. When this action takes place, the valve 17 closes the port 20 again from the receiver and opens communication between the brake-cylinder and an exhaust-port 30. (See Fig. V.)

I claim as my invention—

1. The combination of a train-pipe, a receiver-pipe and brake-cylinder pipe, a chamber, a port forming communication between the chamber and the train-pipe, a piston located in said chamber, a second chamber, a piston located therein, a stem connecting said pistons, a port 18, forming communica- 95 100

tion between said chambers, passing around the pistons, and a port 20, communicating with the receiver-pipe and port 18 and having a separate mechanically automatically operated 5 valve therein, substantially as and for the purpose set forth.

2. The combination of a train-pipe, a receiver-pipe, a brake-cylinder pipe, a chamber, a port 4, forming communication between the 10 chamber and the train-pipe, a piston located in the chamber, a second chamber, a piston located in said second chamber, a stem connecting the pistons, a port 18, extending around both pistons and forming communication between said chambers and the receiver-pipe, a port 20, forming communication between the receiver-pipe and the brake-cylinder pipe, a separate valve located in 15 said port, and a mechanical connection between said valve and said stem, substantially as and for the purpose set forth.

3. The combination of a train-pipe, a receiver-pipe, a brake-cylinder pipe, a chamber, a port forming communication between the 20 said chamber and train-pipe, a piston located in said chamber, a second chamber, a piston located in said second chamber, a stem connecting said pistons, a rack on said stem, a port extending around both pistons and forming 25 communication between said chambers and the receiver-pipe, a port forming communication between the receiver-pipe and the brake-cylinder pipe, and a valve located in said last-mentioned port and provided with a segment engaging a rack, substantially as and for the purpose set forth.

4. The combination of the train-pipe, a brake-cylinder pipe, and a receiver-pipe, valves controlling the passages between said 30 pipes, and an enlargement 6, having flanges 8, forming a passage 7, arranged as shown, substantially as and for the purpose set forth.

5. The combination, with the brake-cylinder pipe and the receiver-pipe, of two chambers, each having a piston therein, a stem connecting said pistons, the train-pipe communicating permanently with the outer end or side of one of said chambers, a port 18, communicating with the same chamber at a point remote from the train-pipe and leading 50 to the outer end of the other chamber around the piston therein, an automatic check-valve in port 18 opening away from the train-pipe, a port having a valve 17 therein connecting the receiver and brake-cylinder pipes together, and a connection between the said stem and valve 17, whereby the latter will be operated automatically, substantially as set forth.

6. The combination, with the train-pipe, receiver-pipe, and brake-cylinder pipe, of two chambers, each having a piston therein, a stem connecting said pistons, a port extending around said pistons and communicating with said chambers on the remote sides of the 65 pistons and with the train-pipe and receiver-pipe, the port 20, having an exhaust connecting the receiver-pipe and train-pipe, a three-way cock in said port 20, a segment on said cock, and a rack on said stem engaging said 70 segment, substantially as set forth.

7. The combination, with the train-pipe, the receiver-pipe and the brake-cylinder pipe, of two chambers, each having a piston therein, a stem connecting said pistons, a port connecting said chambers with the receiver-pipe, a port 20, connecting the receiver-pipe with the brake-cylinder pipe, a cock in port 20, a segment on said cock, a rack on said stem engaging said segment, the guide 15, and an 75 80 arm on said stem engaging in said guide for preventing the revolution of said stem, substantially as set forth.

FRANK LANSBERG.
